(57) CLAIM

The ornamental design for a bag, as shown and described.

DESCRIPTION

FIG. 1 is a rear perspective view of the bag showing my design thereof;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines of the bag and strap represent stitching and form part of the claimed design.

1 Claim, 4 Drawing Sheets

FIG. 4

FIG. 5

FIG. 6

FIG. 7
